UNITED STATES PATENT OFFICE

162,965

CAP OR SIMILAR ARTICLE

Rose Krieger, North Hollywood, Calif.

Application November 24, 1950, Serial No. 13,111

Term of patent 14 years

(Cl. D3—13)

To all whom it may concern:

Be it known that I, Rose Krieger, a citizen of the United States, residing in North Hollywood, county of Los Angeles, State of California, have invented a new, original, and ornamental Design for Cap or Similar Article, of which the following is a specification, reference being had to the accompanying drawing, forming part thereof.

I claim:

The ornamental design for a cap or similar article, substantially as shown.

ROSE KRIEGER,
